UNITED STATES PATENT OFFICE.

HENRY A. PAYNE AND EDWARD M. PRIPPS, OF GARY, INDIANA.

WIRE-CUTTING ATTACHMENT FOR ARMY-RIFLES.

1,183,029.

Specification of Letters Patent.

Patented May 16, 1916.

Application filed September 2, 1915. Serial No. 48,734.

To all whom it may concern:

Be it known that we, HENRY A. PAYNE and EDWARD M. PRIPPS, citizens of the United States, residing at Gary, in the 5 county of Lake and State of Indiana, have invented certain new and useful Improvements in Wire-Cutting Attachments for Army-Rifles; and we do declare the following to be a full, clear, and exact description of the invention, such as will enable 10 others skilled in the art to which it appertains to make and use the same.

Our invention relates broadly to improvements in wire cutters and more particularly 15 to those designed for application to army rifles whereby entanglements of wire particularly barbed wire, may be easily cut and removed.

The object of the invention is to provide 20 a device of this class which although being of extremely simple and inexpensive construction, will be highly efficient and durable and will possess a number of advantageous characteristics.

With this general object in view, the invention resides in certain novel features of construction to be hereinafter fully described and claimed, the descriptive matter being supplemented by the accompanying 25 drawing wherein:

Figure 1 is a side elevation of a portion of an army rifle showing the application of the invention thereto; Figs. 2 and 3 are vertical transverse sections as seen on the 30 planes indicated by the lines 2—2 and 3—3 of Fig. 1 respectively, and Fig. 4 is a perspective view of the stationary cutting blade.

In this drawing which constitutes a part 40 of the application, similar reference characters designate corresponding parts throughout the several views, the numeral 1 having reference to an approximately L-shaped cutting blade whose horizontal arm 2 is 45 beveled to a cutting edge 3 on its upper side, while extending laterally from the upright arm 4 of the blade in a direction opposite to that in which the arm 2 extends, is a finger 5 designed for attachment to the barrel of 50 a gun in a manner yet to be set forth, the finger being preferably formed with a pair of openings 6.

Pivoted at one end to the blade 1 is a 55 horizontal lever 7 having the portion of its body immediately adjacent its pivoted end beveled to form a cutting edge 8 spaced

above the edge 3, while the opposite end of said lever is curved downwardly at 9 and is then continued again horizontally as disclosed at 10, terminating in an eye 11 in 60 which a ring 12 is mounted for the reception of the usual shoulder strap 13.

As clearly shown in Fig. 1, the downwardly extending portion 9 of the lever 7 is provided with a curved cam nose 14 which 65 projects longitudinally therefrom and which is designed for coaction with a keeper yet to be described which is carried by the rifle. By this means, the lever 7 may be normally held in horizontal position, but may be released at will and may then be moved downwardly to move the edge 8 toward the cutting edge of the blade 1.

In applying the invention to use, a bolt, screw or the like 15 is passed through the 70 usual ears 16 which depend from the collar 17 at the front end of the rifle 18, and in addition to this attaching means, a clip 19 preferably surrounds the fire arm in rear of the collar 17, whereby an additional bolt 75 20 may be passed through the other opening 6 and through parallel ears 21 depending from said clip. The lever 7 now lies in close proximity to the rounded lower edge 80 of the rifle barrel and is held in such position by a keeper 22 in the form of a pivoted U-shaped loop carried by the usual clip 83, and receiving therein the cam nose 14. The under side of this nose is curved on an arc 85 extending spirally in respect to the pivot of the keeper 22, whereby as said keeper is forced in one direction, the amount of friction between it and the nose 14 may be increased, thereby maintaining an effective 90 connection.

When the invention is applied to a rifle in the manner above set forth, it is of great utility for cutting barbed wire or in fact any style of wire such as those used in constructing entanglements for military purposes. Obviously, in order to position the wire to be cut between the two edges 8 and 3, it is simply necessary to hold the gun with the lever 7 resting on said wire, to then 100 pull the fire arm rearwardly, and finally to 105 force downwardly on the aforesaid lever.

From the foregoing description, taken in connection with the accompanying drawing, it will be obvious that although the invention is simple and inexpensive, it will be 110 efficient, reliable, and durable. Furthermore, the weight of the gun is increased

only a slight amount and the article is not at all cumbersome.

We claim:

1. A wire cutter comprising a rigid blade 5 having its upper side sharpened to a cutting edge, a horizontal attaching finger formed integrally with one end of the blade and offset upwardly therefrom, a horizontal lever fulcrumed at one end to the blade and 10 extending in a direction opposite to that in which the finger projects, said lever having a cutting edge spaced above that of the aforesaid blade, and means for normally preventing downward movement of the 15 lever.

2. A wire cutter having means whereby it may be attached to a rifle, said cutter be-

ing equipped with a horizontal operating lever, the free end of the lever being extended downwardly and formed with an eye 20 for the anchorage of the shoulder strap of the rifle, and a nose projecting longitudinally from the downwardly extending portion of said lever for reception in a keeper carried by the rifle.

In testimony whereof we have hereunto set our hands in presence of two subscribing witnesses.

HENRY A. PAYNE.
EDWARD M. PRIPPS.
